UNITED STATES PATENT OFFICE.

JOHN L. McMILLAN, OF SYRACUSE, NEW YORK.

LOOSE-LEAF BINDER.

No. 857,252.

Specification of Letters Patent.

Patented June 18, 1907.

Application filed June 2, 1902. Serial No. 109,981.

To all whom it may concern:

Be it known that I, JOHN L. McMILLAN, a citizen of the United States, residing at Syracuse, in the county of Onondaga and State of New York, have invented certain new and useful Improvements in Loose-Leaf Binders, of which the following is a specification.

My invention relates to binders for books or packages of leaves or sheets, or to that class of devices now commonly known as "loose-leaf binders." Binders of this character are at this time coming into quite extensive use for so-called "loose-leaf ledgers" and for other books which, as ordinarily made up, are very costly because of the heavy and elaborate bindings usually employed and indeed necessary. By the use of loose-leaf binders a cover of good quality may be used for a large number of ledgers or other books, the leaves of which, as the pages are filled, may be removed and replaced by fresh ones, the filled leaves being placed in cheaper permanent bindings or otherwise cared for as found expedient. Owing to the large size of books of this character it is essential that the binding devices be made of great strength, and it is also important that the covers and the leaves be free to fold back and present a flat, or substantially flat, surface when the book is opened. I obtain these several ends by the construction represented in the annexed drawings, wherein,

Figure 1 is a face view or elevation of the binder with the covers or boards thrown back, and with all the leaves removed; Fig. 2 an end view of the same; Fig. 3 also an end view, the latter, however, showing the leaves in place and the holding devices forced together to clamp and bind the leaves, whereas Figs. 1 and 2 show them drawn out and nearly separated; Fig. 4 a longitudinal sectional view, taken through the middle of the binding or clamping device, or just to one side thereof; Fig. 5 a perspective view of the wedge mechanism by which the clamping members are thrown inward and caused to clamp or bind the leaves; Fig. 6 a side view, partly in section, and an end view of a key or wrench for actuating the clamping devices; and Fig. 7 a view of a portion of a sheet illustrating one method of notching or perforating the edges thereof.

In constructing my improved binder I aim to preserve, as far as practicable, the general shape and appearance of ordinary bindings for this class of leaves, and particularly to

avoid any actual openings in the back or middle portion connecting the cover boards; yet the device would be operative even though the provision made for closing the space between the two members constituting the back, or middle portion of the back in the construction here shown, were omitted.

Referring now specifically to the drawings: A and B indicate cover boards, united by flexible or hinge portions *a* to curved back members C, which members are in turn united by a hinge formed of two curved plates D and E, each provided with a series of ears or lugs *b*, the lugs on the two plates being arranged to overlap and united by a hinge rod or spindle F. The rod or spindle F is threaded through a portion of its length and screws into or through a pair of lugs *c* similar to the lugs or ears *b*, but heavier or of greater thickness, to allow adequate body for the screw-threads. Either lug or the pair of lugs *c* may be internally threaded, as desired, the threading of both better insuring a maintenance of the proper relative positions of the two curved plates D and E.

The inner or proximate edges of the curved plates D and E are cut away at about their mid-length to form reversely inclined edges *d*, or in other words, to form a triangular space or opening, as best seen in Figs. 1 and 5.

G indicates a block swiveled upon the rod or spindle F, and carrying at its lower side a wedge-shaped or triangular portion *e*, which is of a size to fill, or nearly fill, the triangular opening *d* when the cover is opened out to its fullest extent, or in other words, when the plates D and E are brought as near together at their proximate edges as the parts will permit.

The outer edges of the plates D and E are curved inwardly or away from the back members C, as best shown in Figs. 2 and 3, and to these inwardly curved edges are hinged or pivotally attached alternate solid and tubular impaling pins or members *f* and *g*, the solid pins *f* being arranged to slide or telescope within the tubular members *g*, as indicated in Figs. 1, 2, 3 and 4.

The movement of the members C of the back and of the plates D and E carried by said members is such, relatively to the length of the impaling pins *f*, *g*, as to permit the withdrawal of the pins *f* from their sheaths or tubular sections *g* when the back is opened to its fullest extent. The pins *f* and the sheaths or outer sections *g* are both made

with conical or tapering ends, to facilitate the insertion of the sheaths through openings in the sheets to be bound and the subsequent insertion of the pins within said sheaths.

H indicates a folded or plaited cover strip uniting the proximate edges of the curved back pieces or members C, and serving to cover the mechanism of the back and preventing dust or dirt from entering the opening between said members.

The hinge rod or spindle F may be made polygonal or of other form, to receive a key or wrench by which to turn it, and thus to screw it longitudinally through the lugs c. By such movement the spindle, and with it the swivel-block G, will be carried lengthwise of the back or middle portion C of the cover, the inclined faces of the wedge e bearing against the corresponding inclined faces of the curved plates D and E, and forcing the same to swing around the hinge rod F and to throw toward each other the edges to which are hinged or pivoted the impaling pins f, g. In the present instance, the hinge rod or spindle F is provided with a radial seat or notch h, to receive radial pins or a rod i in a socketed wrench I, shown in Fig. 6. Obviously the form of the wrench and the manner of its engagement with the hinge rod or spindle is a matter of option, variable at will.

The cover or binder being constructed as above described, its operation is as follows: The necessary leaves or sheets to constitute the book are perforated near one edge, the perforations being of a size and form to permit the impaling pins f, g to pass freely through them, but without unnecessary play. The sheets so perforated are passed over or strung upon alternate pins f and sheaths g of one of the curved plates D, E, and the companion pins and sheaths are then placed end to end and pressed lightly together until all the pins are entered. The rod or spindle F is then turned by means of the wrench to rock or swing the plates D, E about said rod or spindle, thereby throwing toward each other the edges of said plates to which the impaling pins are hinged. This movement continues under the force exerted by the screw and the wedge until the edges of the plates D, E bear directly against the sheets and compress them into a firm and compact mass or body, as indicated in Fig. 3. The plates D and E are made quite heavy, as are also the screw and the wedge, so that a very considerable force may be exerted and great pressure applied to clamp and bind the sheets in place, thereby precluding any shifting or displacement of individual leaves or sheets, and maintaining throughout the use of the device the form given to the leaves of the book as a body or book proper.

The impaling pins f, g I regard as very desirable, since they give a positive hold for

and support to the leaves or sheets, but it is possible to use the device without these pins, and to simply clamp or bind the leaves or sheets between the gripping edges of the plates D and E. While, therefore, my invention in its more perfect embodiment includes the impaling pins, it is to be understood that it is not restricted to their use, but that I may also clamp or bind regardless thereof.

Referring to Fig. 7, it will be seen that the sheet is formed with circular openings j, with a cut-away section or opening k, which extends into the circular opening j. The walls of the opening k are inclined toward each other from the edge of the sheet so as to form points or projections l. While the impaling pins f and g pass through the circular openings j and the sheets will ordinarily be held thereon whether the parts are in their clamped position or not, should it be desired to remove a sheet for any purpose, the construction of the sheet just described will permit the withdrawal of one sheet without disturbing the others, the points l on the sheet which is being withdrawn giving way or bending to one side against a pull exerted upon the sheet, while the points upon the adjacent sheets which are not to be removed will maintain their position and retain the sheets in place. From this it will be seen that any one sheet may be withdrawn without the necessity of removing all of the others from the impaling pins. It is to be understood, however, that a sheet thus formed is not absolutely essential to the use of the binder.

The parts here shown may be duplicated or multiplied as desired. Thus, for instance, two or more wedge-blocks may be used, and the rod F may be threaded through more than a single pair of lugs. These and like variations are within the scope and spirit of my invention but come rather within the province of the mechanic than of the inventor. The cover may be of any desired materials, and of a size to suit the various demands.

It is obvious that instead of pivoting the impaling pins, the now common curved pins arranged to pass each other may be employed, but not to so great advantage, it is thought, as the telescopic pins shown.

Having thus described my invention, I claim:

1. A binder for books, leaves or sheets, comprising cover-boards and a back portion to which the cover-boards are flexibly connected, said back portion being formed of two parts hinged together; and means applied to the back portion and serving to force toward each other the edges of said back portion on that side of the hinge axis on which the leaves or sheets are located.

2. A cover or binder comprising plates D and E hinged together; cover-boards A and

B flexibly connected to said plates; a wedge interposed between the proximate edges of said plates; and means, substantially such as described, for forcing said wedge between 5 said plates and causing them to swing about their hinge rod and to clamp sheets or leaves placed between the edges thus moved toward each other.

3. A binder or cover comprising curved 10 back members C; curved plates D and E secured to said back members, hinged together and provided with inclined faces or edges d; cover-boards A and B flexibly connected to the back members C; a screw rod 15 or spindle F movable longitudinally relatively to the back members; and a block G swiveled upon the screw rod and provided with a wedge block e, said wedge block being located between the inclined faces or edges 20 of the plates D and E and adapted, when rod F is moved lengthwise, to force apart the proximate edges of the plates D, E and thereby to move toward each other the opposite edges of said plates and thus to clamp 25 or bind the sheets or leaves introduced between them.

4. The herein-described binder, comprising cover-boards A, B; back sections or members C; curved plates D, E; longitudinally-movable hinge rod F; block G movable longitudinally of said rod but held against rotation therewith; and wedge e carried by 30 said block, interposed between the plates D and E and adapted, when moved longitudinally, to swing said plates about their hinge axis and thus to throw toward each other the opposite or remote edges of the plates.

5. The herein-described binder, comprising cover-boards A, B; back sections or 40 members C; plates D, E provided with ears or lugs b and c; hinge rod or spindle F

threaded in the lug c; block G movable lengthwise of the hinge rod but held against rotation therewith; wedge e carried by block G and interposed between plates D and E; 45 and telescopic impaling pins f, g, carried by the plates D, E, all substantially as shown and described.

6. In a binder, the combination with cover-boards; of a back formed of two parts and 50 provided with plates D and E hinged together and having inturned edges on that side of their hinge axis toward the cover-boards; and means G, such as described, for swinging the plates D, E about their hinge 55 axis and causing the inturned edges of said plates to grip or bind and compress a package of leaves or sheets placed between them.

7. A binder consisting of a frame; telescopic supports for the leaves or sheets; and 60 jaws suitably supported and adapted to move toward or away from each other, the plane of movement of which is at an angle to the plane of said supports.

8. A cover or binder, comprising in combination, a back formed of two sections or members hinged together; cover-boards flexibly connected with said back sections; gripping or clamping plates carried by the back sections; means for forcing the gripping 70 plates toward each other; and a plaited or bellows-like cover strip connecting the proximate edges of the back sections; substantially as shown and described.

In testimony whereof I have signed my 75 name to this specification in the presence of two subscribing witnesses.
